PREFABRICATED FIREPLACE

William G. Hardt, 19 Shady Lane,
Lake Geneva, Wis.

Filed Nov. 22, 1971, Ser. No. 201,250

Term of patent 14 years

Int. Cl. D23—03

U.S. Cl. D23—94

FIG. 1

FIG. 2

FIG. 3

FIG. 4

FIG. 5

FIG. 1 is a perspective view of the prefabricated fireplace showing my new design;

FIG. 2 is a front elevational view of the prefabricated fireplace of FIG. 1 on an enlarged scale;

FIG. 3 is a right side elevational view thereof, the left side being a mirror image thereof;

FIG. 4 is a rear elevational view thereof; and

FIG. 5 is a top plan view thereof.

I claim:

The ornamental design for a prefabricated fireplace, substantially as shown and described.
